UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

FOLDING MECHANISM.

Original application filed July 13, 1921, Serial No. 484,387. Divided and this application filed October 2, 1923. Serial No. 636,131.

To all whom it may concern:

Be it known that I, HOWARD M. BARBER, a citizen of the United States, and resident of Stonington, in the county of New London and State of Connecticut, have invented a new and useful Improvement in Folding Mechanism, of which the following is a specification.

The object of my invention is to provide novel means in a sheet folding machine for making three parallel cross folds, said means including two pairs of folding cylinders coacting to make the three parallel cross folds, one of said cylinders being arranged to coact with one of the other cylinders to make the second fold and with another of the cylinders to make the third fold.

A practical embodiment of my invention is represented in the accompanying drawing, in which—

The figure represents a diagrammatic view of so much of a sheet folding machine as includes my invention.

The web feed roll is denoted by 1 and the pair of coacting rotary cutters by 2, 3, the knives 4, 5 of which are arranged to sever sheets of a predetermined length. The mechanism for imparting three parallel cross folds to the sheets includes two pairs of rotary folding cylinders, the first cylinder being denoted by 6, the second cylinder by 7, the third cylinder by 8 and the fourth cylinder by 9. The first cylinder 6 is shown as provided with a set of head grippers 10 and a floating folding blade 11. The second cylinder 7 is shown as being provided with a set of floating folding jaws 12 arranged to coact with the folding blade 11 to impart a first cross fold to successive products. This second cylinder 7 is also shown as provided with a floating folding blade 14 which is arranged to coact with a set of floating folding jaws 21 on the third folding cylinder 8. The fourth cylinder 9 is shown as provided with a set of head grippers 18 arranged to take the twice folded product from the set of floating folding jaws 21. This fourth cylinder 9 is also shown as provided with a floating folding jaw 19 which is arranged to coact with the second set of floating folding jaws 16 for imparting the third cross fold to successive products.

Coacting friction pulleys 22, 23 are located between the rotary cutters 2, 3 and the

pair of folding cylinders 6, 7 to feed the sheets in register as they pass from the cutters to the first pair of folding cylinders.

The rotary delivery cylinder 24 is provided with a set of head grippers 26 for coaction with the set of floating folding jaws 16, to take the thrice folded products from the third cylinder 8 and deliver the same to the delivery point 28.

A rotary slitter 30 is provided for slitting the thrice folded product longitudinally, said slitter being arranged to coact with the delivery cylinder 24.

Friction pulleys 32 may be provided in position to coact with the cylinder 24 for ensuring the proper delivery of the thrice folded product to the delivery point 28.

I have not shown the means for rotating the several cylinders nor the means for operating the floating folding blades and jaws or the means for operating the head grippers, as all of these means may be of well known or approved construction, readily understood by persons skilled in this art.

It is evident that various changes may be resorted to in the construction, form and arrangement of the several parts without departing from the spirit and scope of my invention; hence, I do not wish to be limited to the particular embodiment herein shown and described, but

What I claim is:

1. In a sheet folding machine, mechanism operative to make three parallel cross folds including two pairs of rotary folding cylinders, one cylinder of the first pair having a folding blade and the other cylinder having one set of jaws to coact therewith and also having a single folding blade, one cylinder of the second pair having a single folding blade and the other cylinder having one set of jaws to coact therewith and another set of jaws to coact with the folding blade on the second named cylinder of the first pair.

2. In a sheet folding machine, mechanism operative to make three parallel cross folds including four rotary folding cylinders, the first cylinder having a folding blade, the second cylinder having a set of jaws to coact therewith, said second cylinder also having a single folding blade, the third cylinder having a set of jaws to coact with the folding blade of the second cylinder, the fourth cylinder having a folding blade and the

third cylinder having a single set of jaws to coact therewith.

3. In a sheet folding machine, mechanism operative to make three parallel cross folds including four rotary folding cylinders, the first cylinder having a folding blade, the second cylinder having a set of jaws to coact therewith, said second cylinder also having a single folding blade, the third cylinder having a set of jaws to coact with the folding blade of the second cylinder, the fourth cylinder having a folding blade and the third cylinder having a single set of jaws to coact therewith, and a rotary delivery cylinder coacting with the third cylinder to take the thrice folded product therefrom.
4. In a sheet folding machine, mechanism operative to make three parallel cross folds

including four rotary folding cylinders, the first cylinder having a folding blade, the second cylinder having a set of jaws to coact therewith, said second cylinder also having a single folding blade, the third cylinder having a set of jaws to coact with the folding blade of the second cylinder, the fourth cylinder having a folding blade and the third cylinder having a single set of jaws to coact therewith, a rotary delivery cylinder coacting with the third cylinder to take the thrice folded product therefrom, and means for slitting the product on the delivery cylinder.

In testimony that I claim the foregoing as my invention, I have signed my name this 28th day of September, A. D. 1923.

HOWARD M. BARBER.
